ABSTRACT: Apparatus for clamping and hoisting a plurality of substantially horizontally aligned articles. The apparatus is characterized by a pair of oppositely disposed spaced jaws for clamping the articles into an integrated beam assembly and by a retractable auxiliary unit for vertically supporting the intermediate portion of the assembly during the subsequent hoisting thereof.

ARTICLE CLAMPING AND HOISTING APPARATUS

This invention relates to article-handling apparatus and more especially to means for simultaneously loading a plurality of prearranged objects such as poultry coops, crates, cartons, packages, and the like.

It is an object of this invention to provide an apparatus of the class described having means for integrating a plurality of load components into a substantially self-supporting beam assembly prior to the hoisting thereof, in combination with retractable means for vertically supporting the intermediate portion of the assembly during the subsequent hoisting operation.

It is another object of this invention to provide an article clamping and hoisting apparatus comprising a pair of pivoted clamping jaws engageable with the opposite ends of a horizontally disposed load assembly, in combination with means for maintaining the engaging jaw faces in an upwardly and outwardly divergent relationship during the clamping operation to thereby afford vertical support underneath the assembly ends when hoisting.

It is another object of this invention to provide an apparatus of the type described in the immediately preceding paragraph wherein means are provided for adjusting the divergency relationship during the clamping operation or cycle to thereby vary the amount of vertical support at the assembly ends.

Some of the objects of invention having been stated, other objects will appear as the description proceeds when taken in connection with the accompanying drawings, in which:

FIG. 1 is a top plan view of a clamping and hoisting apparatus according to my invention, with portions thereof broken away;

FIG. 2 is a front elevation of FIG. 1, with portions thereof broken away;

FIG. 3 is an elevational view of the left-hand end of FIG. 2;

FIG. 4 is a sectional detail view taken along line 4-4 in FIG. 2;

FIG. 5 is a sectional plan view taken along line 5-5 in FIG. 2;

FIG. 6 is a sectional plan view taken along line 6-6 in FIG. 2;

FIG. 7 is a transverse sectional view taken along line 7-7 in FIG. 2;

FIG. 8 is a detail view similar to the left-hand portion of FIG. 2, but showing the clamping mechanism and load components in hoisting position;

FIG. 9 is a sectional plan view similar to FIG. 5, showing means for adjusting the divergency relationship between the clamping jaws, and

FIG. 10 is a vertical sectional view taken along line 10-10 in FIG. 9.

Referring more specifically to the drawings, the numeral 10 designates a turnhead mount of a conventional hydraulic loader. The mount 10 has framework 11 secured to the lower portion thereof which, in turn, supports assemblies 12 and 13 for engaging and supporting an assembly 14 of load components 14a such as poultry coops, crates or cartons in a manner hereinafter described in detail.

The assembly 12 clamps a plurality of the separate components 14a into an integrated, substantially self-supporting beam assembly 14 and, further, provides a V-type cradle or support for the opposite ends of the horizontal assembly during hoisting maneuvers. Prior to clamping, the components 14a are aligned in a horizontal row or rows, each consisting of one or more layers, after which, suitable spaced clamping jaws 17 and 17' are lowered in substantially parallel vertical positions adjacent the opposite ends of the rows as shown in FIG. 2, preparatory to the inward movement of the jaws toward one another to compress the components into a beam as shown in FIG. 8.

The parts of clamping assembly 12 are symmetrical about its vertical center line and, therefore, one side only of this assembly will be described in detail since the other side operates in an opposite-hand manner. The parts on the opposite-hand side corresponding to those to be described will be given the same reference character with prime notations added.

5 Jaw 17 comprises resilient layer 18 for engaging the left-hand end of assembly 14, a plate 19 for supporting the layer, and a bracket 20 for supporting the plate, said bracket being pivotally secured as at 21 to the lower end of depending bellcrank leg 22 of bellcrank lever 23. Lever 23 is pivotally mounted as at 24 to framework 11 and has a laterally and inwardly extending leg 25, the inner end of which is secured as at 26 to vertically disposed links 27. The upper ends of the links 27 are pivotally secured as at 28 to horizontal rocker bracket 29, which bracket is rockably secured intermediate its ends as at 30 to the lower end of piston rod 31 extending downwardly from hydraulic cylinder 32, the upper end of said cylinder being secured to the aforementioned hydraulic turnhead 10.

15 The jaw 17, in combination with jaw 17', is actuated during the inward movement thereof to cradle the load component assembly 14 and to compress the latter horizontally into a beam preparatory to hoisting maneuvers as stated above. Since the bracket 17 swings bodily inwardly about bellcrank lever pivot 24 from the position shown in FIG. 2 to that shown in FIG. 8 during the clamping operation, it is necessary to provide the pivot 21 to permit the face of jaw to adjust itself against the end face of assembly 14 in a well-known manner (See U.S. Pat. No. 3,273,931). Nevertheless, it is of critical importance to preserve said V-shaped position of the jaws 17 and 17', particularly, in the event the end pressure against the components 14a should occur below the jaw pivots 21 and 21'. For this purpose, a U-shaped bracket 35 is positioned about the bellcrank leg 22 and has the bracket legs secured to the upper portion of jaw plate 19, thereby limiting the clockwise rotation of jaw plate 17 about its pivot 21 and also relative to the associated bellcrank leg 22. The depth of the U-shaped bracket 35 such that jaw 17 will be disposed at an angle A at the beginning of the clamping action, which angle will progressively increase thereafter.

20 Angles A and A1 (FIG. 8) are each measured from a vertical line 33 and, when the parts 17, 22 and 23 are in the initial unclamping positions as shown in FIG. 2, these angles are substantially zero. It will be noted that, prior to the occurrence of clamping engagement between jaw 17 and the end of assembly 14, the bellcrank leg 22 may rotate inwardly through the first part of angle A1 without producing any jaw angularity A. This absence of angularity A is the result of clearance 36 provided between leg 22 and bracket 35 (FIGS. 2 and 5). After the inward rotation of leg 22 has taken up the clearance 36, the angle A will increase at the same rate as angle A1. Thus, the jaw 17 will become rigidly attached to leg 22 to maintain a progressively increasing angle A during endwise clamping pressure as leg 22 swings farther inwardly. Angle A2 is always equal to angle A, and angle A3 equal to angle A1, said angles A2 and A3 being measured from horizontal lines 34 and said angles A and A1 from vertical lines 33. Angles A2 and A3, like angles A and A1 described above, are substantially zero when the clamp assembly is in initial unclamped position as shown in FIG. 2.

25 The lift assembly 13 is employed for adjustably supporting the intermediate portion of the clamped load component assembly 14 at different heights relative to the assembly ends. More specifically, the assembly 13 comprises an inverted L-shaped lever 38 having upwardly and laterally disposed legs 39 and 40 respectively, said leg 40 extending transversely of the clamping axis of jaws 17 and 17' and being pivotally secured as at 41 to framework 11. The inner end of leg 40 has a pin 44 which fits into upright slot 45 in the lower end of portion of piston rod 46 of hydraulic cylinder 47, the upper end of the cylinder being pivotally secured as at 48 to framework 11.

30 The lower end of upright leg 39 has pivotally secured thereto as at 51 one end of an inwardly extending lever 52, the inner end of the lever having integral therewith a bar 53 extending substantially parallel to the clamping axis of jaws 17 and 17'. A spring perch 51a is secured to lever 52 adjacent pivot 51, said perch having the lower end of a spring 66 secured thereto as at 69, the upper end of the spring being secured to the intermediate portion of lever leg 38 as at 70.

Bar 53 slidably supports a plurality of spaced fingers 55 in a position normal to the clamping axis of jaws 17 and 17' (FIG. 7). The inner ends of fingers 55 are adapted to fit between the spaced vertical rods 56 which form the walls of coops 14a and at the same time underneath the top bars 57 of the lowermost row of coops. Fingers 55 are yieldingly urged inwardly toward said clamping axis by compression springs 59, one end of each such spring abutting a collar 55a integral with finger 55, and the other spring end abutting the inside wall surface of bar 53. One end of a strand 62 is connected to bar 53 as at 63 and the other end to the lower portion of piston rod 46 as at 64, the intermediate portion of said strand passing over a pulley 65 mounted approximately midway the upper and lower ends of lever leg 39. Strand 62 is maintained under constant tension by previously described spring 66.

When assembly 13 is in the bold line position shown in FIG. 3, the piston rod 46 and the point 64 are in lowermost positions thereby permitting members 52, 52a, 53 and 55 to assume the extreme counterclockwise position relative to pivot 51. During the initial upward movement of piston rod 46 from the position shown in FIG. 3, the assembly 13 rotates from the bold-line to the dotted line position during which the pin 44 remains in engagement with the upper portion of slot 45. Still farther upward movement of rod 46 will elevate slot 4 while pin 44 and L-shaped lever 38 remains in the dotted line position and until the pin reaches the bottom of the slot as shown in FIG. 4. During the latter movement of rod 46, however, the strand 62 will be drawn upwardly to thereby rotate lever 52, bar 53 and prongs 55 in a clockwise direction about pivot 51 from the horizontal dotted line position to thereby elevate the coops to the desired higher elevation. When rod 46 is elevated to the position shown in FIG. 4, the maximum rotation of members 52, 53 and 55 has occurred. Any further upward movement of rod 46 will rotate the entire assembly 13 bodily in a clockwise direction about pivot 41.

FIGS. 9 and 10 show a modified construction which may be employed to adjust the amount of clearance 36 which determines the instant angle A starts to accumulate and after the bellcrank leg 22 has moved inwardly to clamping position along with jaw 17. For this purpose a modified U-shaped bracket 35a has a cam plate mounted therein as at 6, said plate having radially disposed cam surfaces 5a, 5b, 5c and 5d located at progressively increasing distances from point 6. Four radially disposed holes 7, respectively corresponding to surfaces 5a, 5b, 5c and 5d, are equidistantly spaced from point 6, and a bolt 8 is employed to selectively penetrate these holes so as to hold the desired cam surface opposite the leg 22.

The operation of the apparatus is as follows: A hydraulic loader (not shown) attached to turnhead 10 is used as a support for the previously described assemblies during loading maneuvers. As the cage frame 11 is lowered about the unclamped coop assembly 14, the clamps 17 and 17' are positioned opposite the ends of the lowermost row of coops 14a and with clamping faces 18 and 18' in parallel vertical positions. The lowering of framework 11 and clamping assembly 12 is performed while the hydraulic piston rod 31 and bellcrank arms 25, 25' are in the lowered positions shown in FIGS. 2. After the cage frame 11 and assemblies 12 and 13 are properly positioned about the horizontally arranged coop assembly 14, the cylinder 32 is activated toward up-position causing the components of clamp assembly 12 to assume the position shown in FIG. 8 to thereby compress the coops 14a

into an integrated beamlike construction, and concurrently to form a V-shaped cradle support for the assembly ends with the proximate faces of jaws 17 and 17'.

After clamping the coop assembly 14 into a horizontally disposed V-shaped cradle, the hydraulic cylinder 47 is activated to raise piston rod 46. During the initial upward movement of rod 46, the pin 44 remains in the upper portion of slot 45 while the lever 39 rotates by gravity substantially to the position shown in dotted lined and with the fingers 55 engaging the coops 14a as shown in FIG. 7. Additional upward movement of piston rod 46 for the length of slot 45 will then raise strand 62 to produce clockwise rotation of fingers 55 which, in turn, elevate the intermediate portion of the coop assembly 14 to the desired adjusted position.

15 I claim:

1. Article clamping and hoisting apparatus comprising a means for clamping a plurality of articles into a self-supporting beam assembly substantially aligned with a horizontal axis, releasable means operable independently of said first means and movable transversely of said axis for vertically supporting the intermediate portion of said clamped assembly, and hoisting means for supporting said two first-named means.

2. Article clamping and hoisting apparatus as defined in claim 1 wherein said clamping means comprises a pair of spaced arms swingably mounted for movement toward one another, a pair of oppositely disposed clamping jaws pivotally mounted on the free ends of said arms respectively, the proximate faces of said jaws being engageable with the opposite ends of said assembly, and means including said horizontal axial clamping stress and operable concurrently with the inward movement of said arms for rigidly locking said jaws against pivotal movement and for fixing the jaw faces in upwardly and outwardly juxtaposed divergent positions.

3. Article clamping and hoisting apparatus as defined in claim 1 wherein said hoisting means includes a framework, and wherein said intermediate supporting means includes a lever swingably mounted upon said framework and prong means on the free end of said lever and engageable with said assembly.

4. Article clamping and hoisting apparatus as defined in claim 3 and further comprising means for adjusting said prong means and the engaged intermediate assembly portion to different elevations relative to said engaged assembly ends.

5. Article clamping and hoisting apparatus comprising means for clamping a plurality of articles into an integrated assembly substantially aligned with a horizontal axis, means movable transversely of said axis for supporting the intermediate portion of said assembly, and hoisting means for supporting said two first-named means, said clamping means comprising a pair of depending spaced arms swingably mounted for movement toward one another about horizontal axes respectively, a pair of oppositely disposed clamping jaws pivotally mounted on horizontal axes at the lower free ends of said arms respectively, each of said jaw pivots being disposed intermediate the upper and lower ends of the associated jaw whereby the proximate faces of the jaws rotate to adjusted engaged positions against the assembly end in response to the initial clamping pressure, and means for maintaining said proximate jaw faces in upwardly and outwardly relative divergent positions in the succeeding clamping pressure.

6. Apparatus as defined in claim 5 and further comprising means for adjusting the amplitude of said jaw divergency.
